UNITED STATES PATENT OFFICE.

JOHN F. DOWNEY, OF PROVIDENCE, RHODE ISLAND, ASSIGNOR TO UNIVERSAL ASH TRAY COMPANY INC., OF PROVIDENCE, RHODE ISLAND, A CORPORATION OF RHODE ISLAND.

ASH-TRAY.

1,372,124.

Specification of Letters Patent. Patented Mar. 22, 1921.

Application filed June 17, 1920. Serial No. 389,778.

To all whom it may concern:

Be it known that I, JOHN F. DOWNEY, a citizen of the United States, residing at Providence, in the county of Providence and State of Rhode Island, have invented 5 certain new and useful Improvements in Ash-Trays, of which the following is a specification.

This invention relates to a combined ash-tray and cigarette-extinguishing device, and 10 has for its object to provide a simple and inexpensive device of this character which may serve as a table ornament and also as an ash receiver, the same comprising a base having 15 one or more holes in its face, of a size and depth to receive the lighted end of a cigarette, whereby when placed therein the fire will be at once smothered and so extinguished.

20 A further object of the invention is the provision of a removable bushing in the bores of the base whereby the bushing which forms a cup, may be readily removed to clean and discharge the ashes therefrom.

25 By the use of this device any desired number of cigarette-receiving pockets may be formed in a single ash-tray or base.

30 The nature and advantages of the invention will be better understood when the following detail description is taken in connection with the accompanying drawings, the invention residing in the combination and arrangement of parts as claimed.

35 In the drawings forming part of this specification, like numerals of reference indicate similar parts in the several views and wherein:—

40 Figure 1 is a sectional elevation on line 1—1 of Fig. 2, showing my improved ash tray.

Fig. 2 is a plan view of the same.

45 Fig. 3 is a perspective view showing one of the bushings removed from the ash tray or base.

Fig. 4 is a sectional view illustrating a portion of an ash tray, showing the hole in the base portion thereof which is adapted to receive and smother the lighted end of a cigarette.

50 As is well known by cigarette smokers a lighted cigarette upon being laid down in a tray or elsewhere, continues to burn until the whole is consumed, which often is very

objectionable and annoying particularly to the non-smokers in the room.

It is also well known that considerable manipulation is usually required in order to extinguish a lighted cigarette. Therefore it is found desirable to provide means whereby the cigarette may be readily extinguished without effort on the part of the smoker, which result is accomplished by simply placing the lighted end of the cigarette into any one of the holes provided in the base for this purpose.

65 The following is a detailed description of one means by which this extinguishing effect may be readily accomplished:—

With reference to the drawings, 10 designates the base member of an ash tray or receiver, which may be formed of a block of any material and in any desired form, which block may if desired, be provided with a central recess 11 in which is set a removable lining 12 of metal, glass or other suitable material, and this block or base member may also be provided with a plurality of radially-disposed grooves 13 which are adapted to serve as rests or supports for partially smoked cigars.

80 I have also shown this block as being provided with a plurality of holes 14 into each of which is set a thimble-shaped bushing 15 having a central bore 16 of substantially the diameter of a cigarette and of a suitable 85 depth to receive and support the lighted end of a cigarette therein so that when this lighted end is deposited into this recess the fire is at once smothered and extinguished.

These bushings preferably fit loosely into 90 the holes in the block and are provided each with a head portion 17 whereby it may be readily removed to discharge the ashes which may collect therein. Then again this bushing is preferably made of glass or metal so 95 that it will not burn or char by repeated contact with the fire of the cigarette.

By the use of my improved base member any number of cigarette-receiving pockets may be provided and this base may also 100 serve, as illustrated in Fig. 2, for receiving ashes from cigars, and pipes as well as from, cigarettes.

105 I do not wish to be restricted to the provision of a bushing placed in the holes in the base block as the bore of these holes in

the block may be of a size to substantially fit a cigarette, as illustrated at 18 in Fig. 4, if desired.

The device is extremely simple and inexpensive in construction and effective in its operation inasmuch as the lighted end of a cigarette may be readily positioned therein, which operation quickly chokes, smothers and extinguishes the same, without further attention on the part of the user and when a thimble-shaped bushing is employed it may be made of non-inflammable material such as glass or metal to be readily removed for the purpose of discharging the ashes deposited therein.

The foregoing description is directed solely toward the construction illustrated,

but I desire it to be understood that I reserve the privilege of resorting to all the mechanical changes to which the device is susceptible, the invention being defined and limited only by the terms of the appended claim. 20

I claim:

An ash tray comprising a base recessed to receive ashes and provided with a hole of a substantial depth in its face, said hole having a closed bottom portion and said hole being of a diameter to approximately fit and adapted to receive the lighted end of a cigarette so that said end will engage the bottom 30 of the hole to smother and at once extinguish the fire therein.

In testimony whereof I affix my signature.
JOHN F. DOWNEY.
